UNITED STATES PATENT OFFICE.

WILLIAM Y. STROH, OF PITTSBURGH, AND JAMES THOMPSON, OF OAKMONT, PENNSYLVANIA, ASSIGNORS TO CATHERINE STRAYER, OF PITTSBURGH, PENNSYLVANIA.

ART OF TREATING CASTINGS.

Application filed December 30, 1919. Serial No. 348,336.

To all whom it may concern:

Be it known that we, WILLIAM Y. STROH and JAMES THOMPSON, both citizens of the United States, and residing, respectively, in Pittsburgh, Allegheny County, Pennsylvania, and Oakmont, Allegheny County, Pennsylvania, have invented a new and useful Improvement in the Art of Treating Castings, of which the following is a full, 5 clear, and exact description, reference being had to the accompanying drawings, forming part of this specification, in which—

Figure 1 is a side elevation of one form of apparatus which may be used in carrying 10 out our invention.

Figure 2 is a vertical section of the same.

Figure 3 is a face view of the hammers on a larger scale.

Figure 4 is a section on the line IV—IV 20 of Figure 2.

Figure 5 is a detail sectional view showing the spring seats, and

Figure 6 is a diagrammatic view illustrating 25 one arrangement of the hammer elements with respect to the casting.

Our invention has relation to the art of treating castings, and more particularly to a novel method of finishing the same. The invention, while applicable to castings of 30 various metals, is particularly useful in connection with castings having hardened surface portions which are difficult to finish by ordinary machine methods, and which have hitherto been finished by grinding. This 35 grinding operation is not only a rather slow and difficult one, but is objectionable for this kind of castings owing to the fact that it removes parts of the surfaced hardened portions, leaving the same of unequal thickness 40 over the surface of the casting which is finished.

These objections are overcome by our invention. In accordance with such invention we cast a blank which is approximately 45 of the desired contour and dimensions, but which will necessarily have more or less surface irregularities due to the inherent imperfections in all casting methods. The cast blank is then subjected, either 50 throughout its entire surface area, or only to such portions of such area as it is necessary or desirable to finish, to a series of hammer blows imparted in rapid succession. Prior to receiving these blows the casting 55 is preferably heated to about the proper

forging temperature for that class of metal and is subjected to this hammering action while so heated. During the hammering action the casting is moved as may be necessary to bring the different portions of its 60 surface to be treated to the action of the hammer elements; and the latter are provided with means for positively limiting their maximum stroke in the striking direction. In this manner the surface being 65 hammered is reduced to the desired contour, giving a highly finished surface. By proper manipulation of the casting and of the hammers, this work can be very accurately done. It is also possible to provide the casting 70 with a more or less highly polished surface by these operations.

Our invention, in addition to providing a smooth and more or less polished finished surface, is also advantageous in that the 75 hammering action has a beneficial effect upon the metal by way of toughening it and thereby provides a casting with a more or less toughened surface portion. Manifestly, our invention can be carried out by the use 80 of a great variety of apparatus. For the purpose of illustration, we have herein shown and described one form of apparatus suitable for that purpose, said apparatus forming the subject matter of the co-pend- 85 ing application of William Y. Stroh, one of the applicants herein, and George W. Klages, Serial No. 353,665, filed Jan. 24, 1920.

This apparatus will now be described. In these drawings the numeral 2 designates a supporting frame or housing having a base portion which is preferably provided with guides 3 whereby it may be movably mounted upon a suitable support and also 90 having an upright portion 2^a in which certain of the movable parts hereinafter described are mounted.

4 designates a shaft which is mounted in the lower part of said upright portion, in 100 suitable bearings 5 and which is driven in any suitable manner, not shown. Said shaft 4, between the side plates of the upright portion of the frame or housing, has a plurality of eccentrics 6, four in number in the 105 present case. Each of these eccentrics is surrounded by a strap 7 having a depending toe 8 and an upwardly extending lever arm 9. Each of these lever arms extends through a slot in a roller member 10 which is mov- 110

ably seated in a vertically movable slide box 11 mounted in ways or guides 12 of the housing portion 2^a. This slide box may be moved by any suitable means, as by the links 13 connected to opposite ends thereof and also connected to the lever arms 14 of a rocker shaft 15, said shaft being provided at one end portion with an actuating lever 16 which may be held in different adjusted positions by a bolt 17 arranged to work in a slot 18 of the holding member 19. It will be readily seen that by moving the lever 16 to different positions the slide box can be raised or lowered; and as the rollers 10 carried in said slide box form the fulcrums for the eccentric levers, the adjustment of said slide box will vary the effective stroke of the toes 8. These toes 8 are arranged to retract the hammer elements after each blow of the latter. These elements, designated at 20, are removably secured on the outer ends of the plungers 21 which are mounted for horizontal reciprocation in suitable guides 22 in the frame or housing. Said elements may take various forms according to the particular nature of the work to be performed. In the form shown they have a relatively limited contact portion 23 extending transversely thereof; and, preferably, these contact portions, as shown in Figure 3, are staggered or out of line with respect to each other. The said elements have offset lateral edges so as to interfit with each other in the manner indicated in this figure, and thereby strike partially overlapping blows.

The striking impulse is imparted to each plunger by means of a spring 24 seated at one end against a shoulder 25 on the plunger and at the opposite end in a pocket 26 of a seating block 27. This block is slidably mounted in suitable guides 28 in the frame or housing; and each pocket is preferably provided with a follower 29 which is independently adjustable by means of a screw 30. The said elements have offset lateral edges a unit to correspondingly vary the compression of all the springs by any suitable means such as that shown. Such means consist of a hand lever 31 secured to a transversely extending rock shaft 32 and having lever arms 33 at opposite ends which bear against the studs 34 on said block. When the lever 31 is actuated, the block can be moved forwardly against the action of the springs, or can be allowed to move backwardly under the action of the springs. The desired adjustment is maintained by providing the lever members 33 with slots 34 having the locking device 35.

Each of the plungers 21 is provided with the shoulder 36 for engagement with one of the toes 8 whereby, under the action of the eccentric, said plunger is retracted against the action of its spring until the predetermined compression of the spring is reached,

when the plunger is disengaged from said toe and is impelled in a striking direction by the action of the spring. The several eccentrics are at different angles, as indicated in Figure 4, so that the hammer elements strike successive blows.

It is frequently desirable to provide means whereby one or more of the hammer elements may be drawn out of action. For this purpose we provide a rock shaft 37 having a series of fingers 38, each of which is designed to engage a shoulder 39 formed on the underside of the corresponding plunger. The shaft 37 is provided with an actuating lever 39^a. When this lever is moved downwardly from its normal position, shown in Figure 1, the fingers 38 will engage the plungers to retract them. Any desired plunger or plungers may then be locked in this retracted, inoperative, position by inserting a pin through one of the holes 40, provided therefor in the frame or housing and into engagement with the registering hole 41 in the plunger.

The operation of the machine will be readily understood by the foregoing description thereof.

The shaft 4 being continuously rotated, the series of hammer elements will strike a rapid and continuous succession of blows. For the purpose described, it is desirable that means be provided whereby the maximum stroke of each hammer element in the striking direction is limited. For this purpose each of the plungers is provided with a shoulder 42 which, at the limit of the striking blow, contacts with a stop block 43 secured in the frame or housing. In this manner each striking blow is stopped at a predetermined maximum point so that the effect upon the casting being finished is to reduce its surface irregularities to the desired extent and prevent hammer indentations in such surface. The casting to be finished is supported in any suitable manner with respect to the hammer elements. It may, for instance, be supported on a lathe and revolved to the action of these elements; or it may be placed upon any other suitable support, the character of which will depend upon the form of the casting and the particular surface or surfaces thereof to be finished.

While we have shown the machine provided with four hammer elements, we desire it understood that we are not limited to this particular number, but that a greater or lesser number may be employed as may be desired. In some respects superior work may be done with a single hammer element, although this requires more time.

As will be understood the operator in each case is required to manipulate the casting and adjust the hammering apparatus with especial reference to the character of the casting being treated. Such operators will,

however, readily become skilled in this class of work, especially when working with standard forms of castings.

By throwing water upon the heated casting from time to time during the hammering operation, a very considerable degree of polishing may be imparted to the hammered surfaces. This water serves to remove scale in a manner well known in the art of rolling metal plates.

Our invention provides a method of finishing castings which is peculiarly advantageous for the reasons hereinbefore stated.

We claim:

- 15 1. As an article of manufacture, a casting having a finished and polished surface produced directly upon the surface of the casting solely by the action of a series of hammer blows substantially as described.
- 20 2. As an article of manufacture, a cast body of any desired shape having its surface hammer finished and hammer polished, substantially as described.
- 25 3. In the method of treating castings, the steps consisting in casting a blank to approximately the desired shape, heating the same to approximately a forging temperature, and then subjecting the surface or surfaces thereof to be finished to a succession of hammer blows by hammer elements whose contact faces are of relatively small areas, and limiting the maximum stroke of the hammer elements independently of the casting being treated, substantially as described.
- 30 4. In the method of treating castings, the steps consisting in casting a blank to approximately the desired shape, heating the same to approximately a forging tempera-

ture, then subjecting the surface or surfaces thereof to be finished to a succession of hammer blows by hammer elements, and limiting the maximum stroke of said elements independently of the casting being treated, substantially as described.

5. In the method of treating castings, the steps consisting in subjecting a cast blank of approximately the desired shape to a succession of hammer blows, and limiting the maximum strokes of the blow producing element or elements independently of the casting being treated, substantially as described.

6. In the method of treating castings, the steps consisting in casting a blank to approximately the desired shape, then subjecting the surface or surfaces thereof to be finished to a succession of hammer blows, and limiting the maximum strokes of the blow producing element or elements independently of the casting being treated to form a smooth polished surface, substantially as described.

7. In the method of treating castings, the steps consisting in casting a blank to approximately the desired shape, heating the same, then subjecting the portion of the surface to be finished to a succession of hammer blows, and limiting the maximum stroke of each blow producing element independently of the casting being treated to definitely limit the penetration thereof, substantially as described.

In testimony whereof, we have hereunto set our hands.

WILLIAM Y. STROH.
JAMES THOMPSON.

Certificate of Correction.

It is hereby certified that in Letters Patent No. 1,439,454, granted December 19, 1922, upon the application of William Y. Stroh, of Pittsburgh, and James Thompson, of Oakmont, Pennsylvania, assignors to Catherine Strayer, of Pittsburgh, Pennsylvania, for an improvement in "The Art of Treating Castings," an error appears in the printed specification requiring correction as follows: Page 2, line 45, for the words "The said elements have offset lateral edges" read *The slide block 27 can also be adjusted as*; and that the said Letters Patent should be read with this correction therein that the same may conform to the record of the case in the Patent Office.

Signed and sealed this 6th day of February, A. D., 1923.

[seal.]

KARL FENNING,

Acting Commissioner of Patents.
